UNITED STATES PATENT OFFICE.

OSCAR ZERK, NOW BY JUDICIAL CHANGE OF NAME OSCAR ULYSSES ZERK, OF CLEVELAND, OHIO, ASSIGNOR, BY MESNE ASSIGNMENTS, TO ALEMITE MANUFACTURING CORPORATION, OF CHICAGO, ILLINOIS, A CORPORATION OF DELAWARE.

METHOD OF ASSEMBLING VALVES.

Application filed July 5, 1923. Serial No. 649,700.

This invention relates to a method of assembling valve mechanism within a passage in a lubricant feeding nipple, and to a tool for assembling the same.

5 An object of my invention is to provide a tool which during a single operation will advance a coil spring into the passage in a lubricant feeding nipple, and broach the inner wall of the nipple to provide lugs for retaining the spring therein.

Another object of my invention is to provide a tool having broaching teeth and a coil spring retaining seat, or pilot.

Another object of my invention resides in 15 providing a tool having broaching teeth, and means beyond the ends of the teeth for engaging a coil spring, said means having clearances therein in alignment with the broaching teeth.

20 Another object of my invention resides in the method by which a coil spring is assembled and secured within the passage in a lubricant feeding nipple to exert pressure against a valve member.

25 Another object of my invention resides in the method by which a coil spring is compressed within the passage of a lubricant feeding nipple, and lugs are broached from the inner wall of the nipple to secure the spring under compression within the passage therein during a single operation after assembling a ball valve within the passage.

These and other objects will appear hereinafter.

35 In the drawings Fig. 1 is an enlarged sectional elevation of a nipple with valve mechanism therein and broaching punch in relative position at the finish of the broaching operation, both ends of the spring being coiled; Fig. 2 is a fragmentary view of the 40 same showing a spring having the end of the spring extending across the coil; Fig. 3 is a perspective view of the broaching and valve assembling tool; and Fig. 4 is an end view of 45 the nipple with the valve mechanism assembled therein.

Referring to the drawings by characters of reference 10 represents a plate forming a part of a punch press for holding a nipple in inverted position, below a holder 11 which is operated by suitable mechanism of any well known type.

The plate 10 is provided with a recess 12 into which a portion of the nipple fits, being

of substantially the same configuration as the outside of the nipple. The nipple 13 has a reduced inlet end 14 and an outlet end 15, and a passage extends therethrough consisting of a chamber 16, and passages 17 and 18 of decreased diameters. The nipple is also 60 provided with hexagonal sides 19, and when inserted into the recess 12 of the same shape, the nipple is thereby secured within the plate for the purpose hereinafter set forth.

The holder 11 is arranged so that it can 65 be centered directly above the nipple, and is provided with a recess 20 into which one end of the shank 21, of the broaching tool 22 is removably secured. A set screw 23 extends through an aperture in the wall of the holder 70 and engages a flattened portion 24 on the shank.

The outer end of the shank is provided with a plurality of spaced clearances 25 having lands 26 therebetween. The ends of the 75 lands are formed as broaching teeth 27 which are provided with inwardly extending rakes 28.

80 A pilot 29 extends from the end of the shank upon which the teeth are formed. The pilot is provided with longitudinally extending curved grooves 30 the center of each of which is in alignment with one of the teeth 27, providing a chip clearance therefor. These clearances form longitudinally extending ribs 31 therebetween which are a part of the pilot and provide the peripheral surface thereof. The ribs extend longitudinally 85 from the end of the shank and centrally relative to the clearances 25, the peripheral diameter of the pilot through the ribs being slightly greater than the diameter of the shank taken at the central point of the clearances 25 adjacent which the ribs extend. The end 32 of the pilot is formed substantially flat to 90 engage the transversely extending end 33 of a coil spring 34, as hereinafter described. The ribs 31 are provided near their outer ends with inwardly extending shoulders 35 which provide a seat which will engage the 95 circular end of a coil spring 34 as shown in Fig. 1.

100 When the nipple 13 has been placed in the recess 12 in the holder plate 10 with the outlet end of the passage therethrough in uppermost position, a closure member such as a ball 36 is dropped into the passage through the outlet end thereof. The ball will engage the

inner wall of the nipple at the junction between the passage 17 and the chamber 16. A coil spring 34 is then inserted into the passage through the outlet end and will engage 5 the ball 36. The broaching punch carried by the holder 11 is then positioned centrally above the chamber 16 of the nipple, and power is applied to move the punch toward the nipple. As this movement continues the 10 end of the pilot is projected into the coil spring and the shoulders engage the circular strand at the outer end of the coil spring. Further continued movement of the punch will compress the spring against the ball 15 within the passage, in advance of the broaching teeth, and the broaching teeth will engage the inner wall of the nipple adjacent the chamber and will punch out strips thereof curling them inwardly within the chamber 20 forming lugs. These lugs will curl inwardly through the clearances in the pilot. The longitudinal position of the lugs determine the tension of the spring against the ball, and the punch is moved into the nipple sufficient 25 distance to project the lugs at the position therein to create the desired pressure upon the ball. When the lugs are formed as desired the mechanism operating the punch is reversed, and the punch is withdrawn from 30 the nipple, during which movement the outer end of the spring will engage the lugs as the seat formed by the shoulders on the pilot passes therethrough.

It will thus be seen that the spring is compressed within the passage in the nipple in advance of the broaching teeth and so held during the formation of the lugs, which lugs will secure the spring compressed within the passage, exerting sufficient pressure against 40 the ball to normally close the passage through the nipple.

In Figs. 2 and 4 I have shown a modified type of spring in which the transverse end 33 is engaged by the flat end of the pilot when 45 the punch is moved toward the nipple. The spring is compressed and the lugs are simultaneously formed in this instance as previously described, and other than the difference in the manner in which the pilot engages the 50 coil spring, the operation and arrangement is the same.

Various changes may be made in details of construction shown and described without departing from the spirit of my invention 55 and the scope of my claims.

What I claim is:—

1. A method of assembling valve mechanism within a passage through a lubricant receiving nipple consisting of holding a nipple, inserting a closure member into the outlet end of the passage in the nipple, inserting a coil spring for engaging the closure member into the outlet end of the passage in the nipple, compressing said spring, broaching lugs from the wall of the nipple and concurrently increasing the compression of said spring so that the upper end thereof is maintained a predetermined distance from the fixed ends of the lugs, and then releasing said spring to permit the upper end thereof to rest on said lugs. 60 65 70

2. That method of assembling valve mechanism within a passage through a lubricant receiving nipple for high pressure lubricating apparatus which consists of holding a nipple, inserting a closure member into the outlet end of the passage in the nipple, inserting a coil spring into the passage through the outlet end thereof, compressing said spring, and then broaching lugs from the wall of the 75 80 85 nipple to support the outer end of said spring and concurrently increasing the pressure of said spring.

3. The method of assembling valve mechanism within a passage through a lubricant receiving nipple consisting of holding a nipple with the outlet end of the passage therethrough exposed, inserting a closure member into the passage through the outlet end, inserting a spring into the passage through the outlet end, and broaching lugs from the wall of the nipple and maintaining the outlet end of the spring a predetermined distance from the wall end of said lugs during the broaching operation. 90 95

4. That method of assembling valve mechanism within a passage through a lubricant receiving nipple which consists of holding a nipple with its outlet end in exposed position, then inserting a valve member into the passage through said outlet end, then inserting a spring through the outlet end, then compressing the spring against the valve member, and then broaching lugs from the wall of the nipple and maintaining the outlet end of the spring in a predetermined relation to said lugs. 100 105

In testimony whereof I hereunto affix my signature this 3 day of July 1923.

OSCAR ZERK.
